UNITED STATES PATENT OFFICE.

WILLIAM H. OSTERMAN, OF FONDA, IOWA.

INTERNAL-COMBUSTION ENGINE.

1,139,713.

Specification of Letters Patent. Patented May 18, 1915.

Application filed May 7, 1913. Serial No. 766,201.

To all whom it may concern:

Be it known that I, WILLIAM H. OSTERMAN, citizen of the United States of America, and resident of Fonda, Pocahontas county, Iowa, have invented a new and useful Internal-Combustion Engine, of which the following is a specification.

The object of this invention is to provide an improved construction for a two-cycle internal combustion engine.

A further object of this invention is to provide an improved two-cycle internal combustion engine having concentric cylinders and sectional pistons.

A further object of this invention is to provide an improved sectional piston for an internal combustion engine, certain sections of said piston being adapted for variable speed movement to allow the passage of gases.

A further object of this invention is to provide an increased inlet capacity for an internal combustion engine.

A further object of this invention is to provide an improved construction and arrangement for air cooling.

A further object of this invention is to provide an improved self-contained muffling exhaust.

A further object of this invention is to provide a rapid and thorough exhaust of burned gases at a low speed.

A further object of this invention is to provide improved means for varying the speed of certain piston sections at times by means of cam devices on the wrist pin.

A further object of this invention is to provide improved means for varying the speed of certain other piston sections by means of cam devices on the pitman.

A further object of this invention is to provide an improved construction for an internal combustion engine in which all the parts are inclosed in the crank case and cylinders and all lateral projections, pockets and by-passes are eliminated.

A further object of this invention is to provide an improved construction for an internal combustion engine in which none of the engine parts are operated by any device connected to the crank shaft except through a wrist-pin and pitman.

A further object of this invention is to provide means for securing double compression in an internal combustion engine. 55

A further object of this invention is to provide facility of access for adjustment or cleaning of the interior.

My invention consists in the construction, arrangement and combination of elements 60 hereinafter set forth, pointed out in my claims and illustrated by the accompanying drawing, in which—

Figure 1 is a sectional elevation of the head end portion of my improved invention 65 and Fig. 2 is a sectional elevation of the crank end portion thereof. Figs. 1 and 2 are to be read together to produce a sectional view of the complete device. Figs. 3 and 4 are cross-sections on the lines 3—3 70 and 4—4 of Fig. 1. Fig. 5 is an elevation of the wrist-pin and connected devices, on an enlarged scale. Fig. 6 is a cross-section on the line 6—6 of Fig. 2.

In the construction of the device as shown 75 the numerals 10, 11 designate mating halves of a crank case and said halves are formed with projecting, registering, apertured ears 12, 13 adapted to be secured together by screw bolts 14. The members 10, 11 of the 80 crank case are formed with suitable bearings for a crank shaft 15 extending transversely therethrough. An outer cylinder 16 is formed on and projects from one (open) side of the crank case and is closed 85 at its opposite end by a head 17 secured in place by screw bolts 18. An inner cylinder 19 is formed with the head 17, is mounted concentrically of and within the cylinder 16 and extends toward the crank case 10, 11. 90 The head 17 is formed with a central priming and starting connection such as at 20 opening to the chamber 21 inclosed by the head end of the inner cylinder 19; and with diametrically opposite ports 22, 23 adapted 95 for the reception of spark plugs (not shown). The spark plug ports 22, 23 open to the annular chamber 24 between the inner and outer cylinders. Ports 25 are arranged in a row circumferentially of the cylinder 19 and afford communication from the inner or compression chamber 21 to the outer or combustion chamber 24, the capacity of which is approximately twice that of the

former chamber. A circumferential gain 26 is cut in the outer wall of the cylinder 19 at the outer ends of the ports 25 and a split valve ring 27 is mounted in said gain and 5 normally closes said ports. The valve ring 27, which preferably extends nearly but not quite around the cylinder 19, is adapted for outward radial movement under pressure. It preferably is beveled at its inner edges 10 and is of slightly less width than the gain 26 so as to provide a slight clearance at each side. Stop pins 28 are fixed to the inner face of the head 17 just outside the cylinder 19, project inwardly from said head and are 15 adapted to limit radial movement of the valve ring 27.

A variable speed piston is composed of four concentric sections, the two inner sections 29, 30 being within the cylinder 19 20 and the two outer sections being between the cylinders 19 and 16. The inmost piston section 29, which is of trunk form and slightly tapering, is formed with a solid or imperforate head 29^a. The other piston sections, 30, 31, 32 are of generally cylindrical form, and the sections 30 and 32, which are the outmost in their respective chambers, are comparatively short relative to the sections 29 and 31. The piston head 29^a is beveled 25 on its periphery and is adapted to fit tightly within the oppositely beveled annular head of the piston section 30 to form a tight joint and solid head completely closing the cylindrical chamber 21. The piston sections 31, 32 have oppositely beveled annular heads adapted to fit together at times to form a tight joint and solid head completely closing the annular chamber 24. The piston sections 30, 31, 32 are provided with packing rings 30^a, 31^a, 32^a engaging the respective walls of the cylinders 19 and 16. A cylindrical shoe 33 is mounted outside the inmost piston section 29 behind the head 29^a and is fixed to said section by spaced radial 40 lugs 34, in this instance four in number, and said shoe engages the inner surface of the piston section 30 slidingly and centers the section 29 and prevents undesirable oscillation thereof. A web 35 is fixed to and projects from the crank end of the inmost piston section 29 and is connected to the crank end of the section 31, beyond the end of the inner cylinder 19, by means of screws 36. The piston section 31 is also formed with an 45 outwardly projecting annular shoe 37 at its crank end engaging the inner surface of the outer cylinder 16 and provided with packing rings 38. A connecting rod or arm 39 is fixed to and projects from the crank end of the piston section 30 and is connected to operating devices as hereinafter described. Operating rods 40, in this instance four in 50 number, are threaded at their ends and screwed into radial lugs 41 on the outermost

piston section 32, extend toward the crank 65 case 10, 11, and pass slidingly through bearings in the piston shoe 37 of the adjacent section 31. The ends of the operating rods 40 pass through end portions of convex plates 42 which are two in number and spaced apart transversely in the rear end portion of the cylinder 19. The ends of the operating rods 40 are threaded and adjusting nuts 43, 44 are screwed thereon on opposite sides of the convex plates 42 and may be 70 employed to compensate for wear.

A wrist pin 45 is fixed to the throw of the crank shaft 15 and a pitman 46 is formed with a suitable bearing (preferably secured by screw bolts 46^a) at one end pivotally engaging said wrist pin. The opposite end of the pitman 46 is formed with a suitable bearing pivotally engaging a piston or gudgeon pin 47 mounted in the crank end of the inmost piston section 29. A lug 48 is formed on and projects inward radially from the connecting rod 39 and a leaf spring 49 is fixed at one end to and carried by said lug. The opposite end portion of the spring 49 is received loosely between converging thumbs or lugs 50, 51 on the end portion of the pitman 46 adjacent the piston pin 47. The thumb or lug 51 is of materially greater length than the thumb or lug 50 and is inclined and arranged so as to bear at times 90 against the spring 49 adjacent the point of attachment thereof to the lug 48. The arrangement of the thumbs or lugs 50, 51 is such that slightly before the end of each up stroke (the wrist pin being about 15 degrees below center) a pressure is applied by the thumb 51 against the spring 49 and lug 48 to the end of increasing the speed of the piston section 30, which normally is reciprocated with the section 29, and causing 100 said section 30 to pass beyond the section 29, and to lag behind said section 29 on the return stroke; and at the end of the stroke the thumb or lug 50 acts through the spring 49, lug 48 and connecting rod 39 to increase the 110 speed of the piston section 30 and cause said section to overtake and again travel with the section 29, forming a solid or compressing head. The pitman 46 is formed with a central longitudinal bore at its crank end 115 in which is mounted a plunger bolt 52. The pitman 46 also is forked at its crank end, as shown in Fig. 5, and a cam 53 is fixed to the wrist pin 45 within said fork and is adapted to engage and reciprocate the plunger bolt 52 at times. A pin 54 is fixed in the inner end of the plunger bolt 52 and projects at its ends through and is adapted to travel in longitudinal slots 55 in the pitman 46. The pin 54 carries on its ends rollers 120 56, 57 adapted to engage and exert pressure on the convex plates 42, one of which 125 is located on each side of the pitman 46.

The convex plates 42 are plane on their upper surfaces and are backed by springs 58 fixed at their ends to the web 35 of the inmost piston section 29. Thus the inmost 5 and outermost piston sections, 29 and 32, are yieldingly connected.

An intake port 59 is formed in the crank case section 11 and is provided with suitable connections to a source of fuel supply such 10 as a carburetor (not shown). Exhaust ports 60 extend in a row around the outer cylinder 16 below the piston sections. The exhaust ports 60 open to an annular muffler chamber 61 formed by a cylinder 62 fixed 15 to and concentrically of the crank end portion of the cylinder 16. The muffler chamber 61 is provided with diametrically opposite discharge ports 63, 64.

In practical operation, fuel gas is sucked 20 in through the intake 59 by each up stroke of the combined piston sections, and partially fills the crank case and lower ends of the cylinders. Just before the end of this stroke, as above explained, the piston section 25 begins to accelerate its speed, passes beyond the section 29, closes the ports 25, and prevents back firing or firing from supercompression in the transfer chamber 21. On the return stroke, the piston section 30 30 now lagging, a passageway is provided for the fuel gas to pass between the sections 29 and 30 and enter the chamber 21, where it is trapped near the end of the stroke by reengagement of said sections. The up 35 stroke again draws in a new charge and compresses the former charge somewhat in the chamber 21, whence it is transferred, when the pressure has reached a certain degree and just before the separation of the 40 sections 29 and 30, through the ports 25 to the chamber 24 by lifting of the valve ring 27. The charge is now further compressed in the chamber 24 by the engaged and combined piston sections 31, 32 and is 45 fired, the two spark plugs acting alternately. This explosion applies an impulse to the engaged and combined sections 31, 32 to the end of beginning the return or power stroke. In this connection, it will be remembered 50 that the section 31 is rigidly connected to the web 35 and thus to the inner section 29 and crank shaft connections. Inasmuch as the capacity of the outer chamber 24 is double the transfer capacity of the inner 21, 55 were no ignition to take place, the charge would reach its normal density at the half-way point of the impulse stroke, the point corresponding to that at which the ordinary gasoline engine begins to exhaust; but 60 ignition having taken place in the chamber 24, the heat units are transformed into mechanical energy and a great advantage in work is obtained, during the latter half of the piston travel, the resulting effect being

that of a compound piston travel with application to the wrist pin at the point of greatest leverage, as illustrated in Figs. 1 and 2 of the drawings. Toward the end of the power stroke, the piston section 32 is caused to lag behind the section 31, because 65 of the engagement of the cam 53 with the outer end of the plunger bolt 52, thus causing a reciprocation of said bolt, a movement of the pin 54, rollers 56, 57, and an application of pressure through said rollers to the 70 convex plates 42, connecting rods 40, lugs 41 and piston section 32. This separation of the piston sections 31, 32 allows the burned gases to escape from the chamber 24 between said sections and to pass through the ports 80 60 into the muffler 61 and thence out through the discharge openings 63, 64. This exhaust of the burned gases causes a reduction of pressure in the chamber 24 and allows a transfer of the next charge from the chamber 21. Thus each complete stroke of the 85 piston witnesses an intake of a fresh charge, a compression in the inner cylinder, a transfer to the outer cylinder, a further compression and an explosion therein, and an exhaust from said latter chamber, and the cycle is repeated for each revolution of the crank shaft.

It is to be understood that a plurality of the units above described, preferably four, 95 are to be used in each complete engine and on one crank shaft, in a common and well known manner, and that the strokes and explosions of adjacent units will alternate.

The large radiating surface of the outer 100 cylinder, and the firing of the charge between two cylinders, provides for effective air-cooling of the cylinders. The use of the sectional piston affords a maximum inlet capacity and reduces frictional resistance to 105 a minimum. The burned gases are exhausted rapidly at a low speed because of the arrangement and location of the exhaust ports and muffling chamber, and there is little danger of clogging or choking up. The 110 exhaust always travels in the same direction and there is no necessity for reversal at any time. The compression and transfer of the air and gas produces a better mixture and more perfect ignition than in a single compression engine. The production of a compound or double piston travel, and the timely arrangement of its application, results in the extraction of a large amount of work from a given amount of fuel. The 115 120 working parts are all contained in one enclosure and there are no exposed parts nor lateral pockets, projections or by-passes.

The parts may be rendered accessible for 125 cleaning and decarbonizing, if necessary, by removal of the head 17, the inner cylinder 19 coming out with the head. By removal of the screw bolts 46 all the working parts

above the crank may be removed for cleaning, inspection, adjustment or repair.

I claim as my invention—

1. An internal combustion engine, comprising a crank case, a crank shaft journaled therein, concentric cylinders communicating with said crank case, concentric piston members arranged for reciprocation in said cylinders, driving connections between said crank shaft and piston, and a muffling chamber concentric with and communicating from the outer cylinder.

2. An internal combustion engine, comprising a crank case, a crank shaft journaled therein, a cylinder communicating with said crank case, a divisible piston in said cylinder, a cylinder arranged concentric with and outside of said first cylinder, a divisible piston of annular form in the outer cylinder, connections between said pistons, and driving connections between the innermost piston and the crank shaft.

3. An internal combustion engine, comprising a crank case, a crank shaft journaled therein, a cylinder communicating with said crank case, a divisible piston in said cylinder, a cylinder concentric with and outside of the first cylinder, a divisible piston of annular form in the latter cylinder, rigid connections between the innermost sections of the respective pistons, and driving connections between the innermost piston section and the crank shaft.

4. An internal combustion engine, comprising a crank case, a crank shaft journaled therein, a cylinder communicating with said crank case, a divisible piston in said cylinder, a cylinder concentric with and outside of the first cylinder, a divisible piston of annular form in the latter cylinder, rigid connections between the innermost sections of the respective pistons, yielding connections between the innermost and outermost piston sections, driving connections between the innermost piston section and the crank shaft, and means connected with said driving connections for varying the speed of the outermost piston section.

5. An internal combustion engine, comprising a crank case, a crank shaft journaled therein, a cylinder communicating with said crank case, a divisible piston in said cylinder, a cylinder concentric with and outside of the first cylinder, a divisible piston of annular form in the latter cylinder, rigid connections between the innermost sections of the respective pistons, yielding connections between the innermost and outermost piston sections, driving connections between the innermost piston section and the crank shaft, means connected with said driving connections for varying the speed of the outermost piston section, and separate means connected with said driving connections for

varying the speed of the outermost section of the inner piston.

6. An internal combustion engine, comprising a crank case, a crank shaft journaled therein, a cylinder communicating with said crank case, a divisible piston in said cylinder, a cylinder concentric with and outside of the first cylinder, a divisible piston of annular form in the latter cylinder, a wrist pin on said crank shaft, a pitman pivotally connecting said wrist pin and the inner piston, and a cam on said wrist pin adapted to separate the sections of the outer piston during each impulse stroke.

7. An internal combustion engine, comprising a crank case, a crank shaft journaled therein, a cylinder communicating with said crank case, a divisible piston in said cylinder, a cylinder concentric with and outside of the first cylinder, a divisible piston of annular form in the latter cylinder, a wrist pin on the crank shaft, a pitman pivotally connecting said wrist pin and the inner piston, and means on said pitman for separating the sections of the inner piston after each compression stroke.

8. In an internal combustion engine, two concentric cylinders, a piston in the inner cylinder, an annular piston in the outer cylinder, valve controlled communication from the inner to the outer cylinder, means for drawing a charge into the inner cylinder through the piston therein, the first piston being adapted for compressing said charge in the inner cylinder and transferring the same to the outer cylinder, the second piston being adapted for further compressing and firing said charge in the outer chamber, and means for exhausting the exploded charge through the annular piston of the outer chamber.

9. In an internal combustion engine, concentric cylinders, a piston in the inner cylinder, an annular piston in the outer cylinder, an annular muffling chamber concentric with and having communication from the outer cylinder, valve controlled communication between the inner and outer cylinders, the inner cylinder being adapted to receive a charge through the piston therein, the first piston being adapted for compressing said charge in the inner cylinder and transferring the same to the outer cylinder, means for exploding said charge in the outer cylinder, and means for exhausting the exploded charge through the annular piston to said muffling chamber.

10. In an internal combustion engine having a crank shaft, a wrist pin thereon, separable piston sections yieldingly connected, and a pitman pivotally connecting said wrist pin and one of said piston sections, a cam on said wrist pin, a plunger bolt mounted in said pitman, a transverse pin in

the inner end of said plunger bolt, rollers on said pin, and means on the other piston section for engagement by said rollers.

11. In an internal combustion engine having a crank shaft, a wrist pin thereon, separable piston sections and a pitman pivotally connecting said wrist pin and one of said sections, a spring fixed in the other of said piston sections and cam devices on said pit-

man and acting upon said spring for alternately slackening and increasing the speed of the latter piston section.

Signed by me at Des Moines, Iowa, this twelfth day of April, 1913.

WILLIAM H. OSTERMAN.
